GUN PLATFORM STABILIZATION SYSTEM
 Frank S. Preston, Fairfield, Conn., assignor to United Aircraft Corporation, East Hartford, Conn., a corporation of Delaware

Filed June 8, 1967, Ser. No. 644,628
 15 Claims. (Cl. 89—41)

ABSTRACT OF THE DISCLOSURE

A system for stabilizing a platform on which a gun is carried on a movable mount spaced from the center of gravity of the platform including means responsive to firing of the gun for generating a signal approximating the torque applied to the platform as a result of the firing and means responsive to the signal for applying a counteracting torque to the platform.

Background of the invention

It is well known that a gun supported on a movable platform or vehicle reacts thereon. Systems are known in the prior art for stabilizing the platform to correct for changes in attitude resulting from external influences. In addition to these external influences, there exists the force of reaction on the platform resulting from firing of the gun. Where the platform or vehicle has a relatively large mass, these reaction forces can be absorbed by various systems such, for example, as a carriage and spring arrangement or by venting gas from the gun barrel.

In some instances, however, the stabilizing arrangements described above are entirely unsuitable. For example, a helicopter or a satellite makes a very poor gun platform in that the reaction force tends to swing the platform unless the reaction force is directed through the center of gravity. While the pilot or some automatic attitude stabilizing system can restore the platform to its initial attitude following a change in attitude resulting from firing, this operation takes appreciable time as compared with the time during which a gun firing at a very rapid rate is fired in short bursts. These factors have resulted in a limitation of the permissible rate of fire consistent with accuracy or they have resulted in inaccurate firing.

I have invented a gun platform stabilization system which, in a rapid and expeditious manner, counteracts the platform torque resulting from firing of a gun. My system permits a gun to be fired at a relatively rapid rate with greater accuracy than is possible with systems of the prior art. My arrangement is simple for the result achieved thereby.

Summary of the invention

One object of my invention is to provide a gun platform stabilization system which acts in a rapid and expeditious manner to counteract the torque exerted on the platform by firing of the gun.

Another object of my invention is to provide a gun platform stabilization system which permits a gun on a relatively light platform to be fired rapidly with a relatively high degree of accuracy.

A further object of my invention is to provide a gun platform stabilization system which is simple in its construction and in its operation for the result achieved thereby.

Other and further objects of my invention will appear from the following description.

In general my invention contemplates the provision of a gun platform stabilization system in which, in response to firing of the gun, I generate a signal which is an approximate measure of the torque exerted on the platform as a result of the firing. I apply the torque signal to a

2

device adapted to apply a torque to the platform, which torque is generally equal and opposite to the disturbing torque resulting from firing of the gun.

Brief description of the drawings

In the accompanying drawings which form part of the instant specification and which are to be read in conjunction therewith and in which like reference numerals are used to indicate like parts in the various views:

FIGURE 1 is a diagrammatic view of a gun and platform to which I may apply my platform stabilizing system.

FIGURE 2 is a diagram illustrating the effect of firing of the gun on two mutually perpendicular axes.

FIGURE 3 is a schematic view illustrating one form of my gun platform stabilizing system.

FIGURE 4 is a schematic view of another form of my gun platform stabilizing system.

Description of the preferred embodiment

Referring now to FIGURE 1 of the drawings, I have shown a platform 10 which may, for example, be a light vehicle, such as a helicopter or a satellite or the like, which carries a gun mount 12 supported for pivotal movement around an axis 14 spaced at a distance d from an axis passing through the center of gravity 16 of the platform 10. By way of example, I have illustrated the direction of movement of the platform 10 by the arrow V on the broken line 20 passing through the center of gravity 16. With the gun 18 oriented at an angle ϕ to the line 20, when the gun is fired there results a reaction force F acting on the platform 10 through an arm l . This action produces a torque T tending to rotate the platform 10 around the center of gravity 16 so that

$$(1) \quad T = Fl$$

The force F can be expressed as some constant k times the rate of change of momentum M or

$$(2) \quad F = kdm/dt$$

The rate of change of momentum is approximately equal to the product of the mass m of a round times the rate of fire r so that we can write

$$(3) \quad F = kmr$$

It can readily be seen that the length of arm l is given by the product of the distance d between the gun pivot and the center of gravity times the cosine of the angle ϕ between the gun barrel 18 and the direction of movement of the craft. Thus

$$(4) \quad T = kmrd \cos \phi$$

I generate a torque equal and opposite to the torque represented by Equation 4 to counteract the effect of firing of the gun on the platform 10.

Referring to FIGURE 2, by way of example I have shown an arbitrary line of fire in space by the large arrow with the gun pivot spaced from the intersection of the roll and pitch axes at the center of gravity of the system. Considering only the effect on the roll and pitch axes, I first projected the space line of fire onto a plane in which the pitch axis lies and onto a plane in which the roll axis lies. Taking first the roll axis, we know that the maximum torque around the roll axis will result if the line of fire is normal to a line representing the distance d_r from the center of gravity to the projected gun pivot. I have represented such a line of fire by the dot-dash line in the figure. The projection of the actual line of fire, however, is not normal to the distance d_r but makes an angle ϕ_r with the normal. It will be clear from the explanation hereinabove that a normal l_r to the projection of the actual line of fire is $l_r = d_r \cos \phi_r$. Knowing this distance we can generate the signal representing the com-

ponent of torque around the roll axis in the manner described above. The component of torque around the pitch axis may be arrived at in a similar manner.

Referring to FIGURE 3, I have shown one form of my compensating system which acts around one axis of the platform 10. I apply a signal $e=E \sin \omega t$ at a terminal 22 to an autotransformer winding 24. The transformer pickoff 26 is adapted to be positioned either manually or in response to a suitable computer through a linkage 28. I so position the pickoff 26 as to provide a signal $e_1=E_1 \sin \omega t$ on a conductor 30 where $E_1=kmrdE$.

The system shown in FIGURE 3 includes a resolver indicated generally by the reference character 32 having a rotor winding 34 and respective stator windings 36 and 38, the latter winding not being employed in my system. I provide a mechanical coupling, indicated by the broken line 40, between the movable mount 12 and the rotor 34 of the resolver 32 to cause the resolver winding 32 to be positioned from a reference direction in accordance with the angle ϕ between the gun barrel 18 and the line 20 of movement of the platform. I also connect conductor 30 to the winding 34. I so select the reference direction that the angle ϕ with respect to a particular axis is the angle between the line producing maximum torque around that axis and the actual line of fire referred to that axis.

From the structure just described it will be appreciated that winding 36 carries an output signal $k_1 E_1 \cos \phi \sin \omega t$. It will further be apparent that this signal is an analog of the torque exerted on the platform 10 around a vertical axis as viewed in FIGURE 3 as a result of firing of the gun. A normally open switch 42 which, preferably, is closed in response to operation of the gun trigger couples the signal on winding 36 to an amplifier 44 which supplies the torque compensating unit indicated generally by the reference character 46 of my system.

It is to be understood that I may employ any suitable arrangement 46 for applying the counteracting torque in response to the signal on winding 36. By way of example, I have schematically shown a reaction wheel including a stationary armature 48 and a movable wheel 50 supported for movement around an axis 52 on the vehicle. Wheel 50 carries means such, for example, as permanent magnets (not shown) which interact with the field resulting from energization of the armature 48 to tend to rotate the wheel. The resulting force provides a reaction torque on the vehicle or platform 10. Preferably wheel 50 is mounted for movement around that axis, passing through the center of gravity, around which compensation is desired. Alternatively, it may be mounted for movement around an axis parallel to the axis around which compensation is desired.

Alternative to the particular torque compensating unit 46 shown, I may employ other arrangements such, for example, as the inertial compensator illustrated in FIGURES 6 to 14 of Patent No. 3,039,096. Still another arrangement might be one wherein an autopilot or auto-stabilizer was actuated to operate through the normal controls of the vehicle.

Referring now to FIGURE 4, by way of a further example I have shown the mount 12 supported on a helicopter 54. As in the form of the system shown in FIGURE 3, the linkage 40 drives the rotor 34 of the resolver 32 in response to movement of the mount 12. In this arrangement a knob 56 can be operated to set the rate of fire by moving a brush 58 along a potentiometer winding 60 which is supplied with the signal $e=E \sin \omega t$ from a terminal 62. It will readily be appreciated that a signal corresponding to that produced by setting knob 56 might be generated automatically by the gun. Brush 58 applies the signal $kmre$ to an operational amplifier 64 which feeds the potentiometer winding 66.

The helicopter 54 includes a pilot's control lever 68 supported on a shaft 70 and normally centered by springs 72 and 74 carried by the feel datum trim unit 76. A link-

age 78 responsive to the lever 68 positions the brush 80 associated with winding 66 as determined by the trimmed datum position of the feel system which, as is known in the art, is proportional to the center of gravity position. Owing to this arrangement, a conductor 82 connected to brush 80 carries the signal $kmrd$. An operational amplifier 84 couples the signal $kmrd$ to the rotor winding 34 of resolver 32 to cause the winding 36 to provide the signal $kmrd \cos \phi \sin \omega t$.

10 A link 86 connects the control lever 68 to a lever 88 coupled by a link 90 to a lever 92 carrying a link 94 adapted to operate a power control 96 for operating a swash plate and driver mix mechanism 98 having an output shaft 100 driving a linkage 102 for positioning the 15 controlled member 104. Since this structure is well known in the art, it will not be described in further detail.

I provide my system with a stabilizer actuator servo loop 106 including an amplifier 108 which supplies a motor 110 to drive a shaft 112 carrying a pinion 114 20 which drives a gear 116 for driving a worm 118 to position the brush 120 of a follow-up potentiometer 122 providing one input to the amplifier 108. The arrangement incorporates a linkage 124 providing an input to a gyro reference 126 supplying an output signal as another input 25 to amplifier 108, which output is a measure of the actual position of the controlled member 104. A tachometer 128 driven by shaft 112 provides a rate input to amplifier 108. I connect the trigger switch 42 to provide the fourth input 30 to the amplifier 108. In this way the automatic stabilizer actuator provides such a control of the surface 104 as to give rise to a torque for compensating the effect of firing of the gun 18.

It is to be understood that except for the input provided by operation of switch 42, the stabilizer actuator servo loop 106 is well known in the art. For that reason, 35 it will not be described in detail. For the purposes of my invention, it is to be understood only that with the input provided by operation of switch 42 when the gun is fired, the system including the loop 106 functions to apply such a torque to the helicopter around the axis under consideration as will compensate for the torque around that axis resulting from firing of the gun. As has been explained hereinabove, my arrangement is not limited to a particular axis but may readily be applied 40 around any axis for which compensation is necessary or desirable. In such a system I use an individual resolver 32 for each of the axes around which compensation is desired. Where I generate a number of signals corresponding to the compensating torques required with reference to the various axes, I use a multiple axis control system to which I feed these signals. By way of example, I may employ a control system such as is shown and described in United States Patent No. 3,071,335.

55 In operation of the form of my arrangement shown in FIGURE 3, for example, where a gun 18 is mounted for pivotal movement around a vertical axis spaced a distance d from a vertical axis passing through the center of gravity, the maximum torque around that axis resulting from firing of the gun 18 will occur when the gun is aligned with the vector V shown in the figure. In such case, the output of resolver winding 36 will be $E_1 \sin \omega t$ where E_1 is equal to $kmrd$ since $\cos \phi=1$. If now the line of fire changes or has to be at an angle ϕ with respect 60 to a line parallel to the vector V , then the signal output from winding 36 will be $E_1 \omega t \cos \phi$ where $\cos \phi$ is less than 1. Stated otherwise, with the actual line of fire at an angle ϕ to the line corresponding to maximum torque, the force is acting through a moment arm l which is less than the distance d and which is $l=d \cos \phi$. The rate of fire can readily be set by moving the brush along 65 the autotransformer winding 24. It will readily be understood that this also might be under the control of the 70 firing of the gun. The manner in which my system can 75

be adapted to a plurality of axes will readily be understood from the showing of FIGURE 2.

In operation of the form of my system shown in FIGURE 4, the rate of fire is set by actuating knob 56 to set brush 58 manually on the resistor 60 or the same resultant signal may be generated automatically. Movement of brush 80 on resistor 66 compensates this system for changes in the center of gravity. With the resultant signal applied to winding 34, then winding 36 produces the signal $kmrd \sin \omega t \cos \phi$ which is applied by the trigger responsive switch 42 as one input to the loop 106 which, in a manner known to the art, causes the compensating torque to be applied to the craft. Where a multiple axis system is employed, a control system adapted to receive inputs corresponding to the respective axes is used.

It will be seen that I have accomplished the objects of my invention. I have provided a gun platform stabilization system for rapidly and expeditiously counteracting the torque exerted on the gun platform as a result of firing the gun. My invention permits a gun mounted on a relatively light platform to be fired rapidly with a relatively high degree of accuracy. My system is simple in construction and operation for the result achieved thereby.

It will be understood that certain features and subcombinations are of utility and may be employed without reference to other features and subcombinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

1. A system for stabilizing a platform with reference to an axis thereof, said platform carrying a gun mounted for movement at a location spaced from said axis to establish a movable line of fire, including in combination, means responsive to firing of said gun for generating a signal representing a disturbing torque applied to said platform around said axis owing to said firing and means responsive to said signal for applying a compensating torque to said platform around said axis to counteract the effect of said disturbing torque.

2. A system as in claim 1 in which said signal generating means comprises means for producing a signal representing the maximum torque resulting from a line of fire of said gun normal to a line from said location to said axis and means responsive to deviation of the actual line of fire from said normal line of fire for modifying said maximum torque signal to provide said disturbing torque signal.

3. A system as in claim 1 in which said signal generating means comprises means for producing a signal proportional to the product of the mass of a round fired by said gun and the rate of fire of said gun.

4. A system as in claim 1 in which said signal generating means comprises a variable transformer having a fixed winding and a movable winding and means responsive to movement of said movable line of fire for moving said movable winding.

5. A system as in claim 1 in which said signal generating means comprises a resolver having a rotor winding and a stator winding, means responsive to movement of said line of fire for driving said rotor winding, means for producing a signal representing the maximum torque resulting from a line of fire of said gun normal to a line from said location to said axis and means for applying said maximum torque signal to said rotor winding.

6. A system as in claim 1 in which said signal generating means comprises a resolver having a rotor winding and a stator cosine winding, means responsive to movement of said line of fire for driving said rotor winding, means for producing a signal representing the maximum torque resulting from a line of fire of said gun normal

to a line from said location to said axis and means for applying said maximum torque signal to said rotor winding.

7. A system as in claim 1 in which said signal generating means comprises a variable transformer having a fixed winding and a movable winding, means for producing a signal proportional to the product of the rate of fire of said gun and the mass of a round fired by said gun, means for applying said product signal to one of said windings and means responsive to movement of said line of fire for driving said movable winding to cause the other winding to provide said disturbing torque signal.

8. A system as in claim 1 in which said compensating torque applying means includes a normally open switch adapted to be closed concomitantly with the firing of the gun.

9. A system as in claim 1 in which said compensating torque applying means comprises an electromagnetic reaction device having a pair of members, means mounting one of said members on said platform for movement therewith, means mounting the other member on said platform for rotary movement with respect to the other member, one of said members being energizable to generate a reaction between said members and means for applying said signal to said energizable member.

10. A system as in claim 1 in which said compensating torque applying means comprises a control surface coupled to said platform, a servo loop for actuating said control surface and means for coupling said signal to said servo loop as one input thereto.

11. A system as in claim 1 in which said compensating torque applying means comprises means for generating a signal representing the product of the force resulting from firing of said gun and the distance from said gun mount to the center of gravity of said platform, a feel datum trim unit and means responsive to said unit for modifying said product signal to compensate for changes in the center of gravity of said platform.

12. A system as in claim 1 in which said signal producing means comprises a resolver having a rotor winding and a cosine stator winding, means for producing a signal proportional to the product of the mass of a round fired by said gun and the rate of fire of said gun and the distance of the gun mount from the center of gravity of said platform, means for applying said product signal to said rotor winding, means responsive to movement of said line of fire for moving said rotor winding to cause said stator winding to provide said disturbing torque signal and a normally open switch actuatable concomitantly with the firing of the gun for applying said disturbing torque signal to said compensating torque applying means.

13. A system as in claim 1 in which said signal producing means comprises a resolver having a rotor winding and a cosine stator winding, means for producing a signal proportional to the product of the mass of a round fired by said gun and the rate of fire of said gun and the distance of the gun mount from the center of gravity of said platform, means for applying said product signal to said rotor winding, means responsive to movement of said line of fire for moving said rotor winding to cause said stator winding to provide said disturbing torque signal, and in which said compensating torque applying means is an electromagnetic reaction device comprising a pair of relatively movable members, means mounting one of said members on said platform for movement therewith, one of said members being energizable to generate a reaction torque between said members and a normally open switch actuatable concomitantly with the firing of the gun for applying said disturbing torque signal to said compensating torque applying means.

14. A system as in claim 1 in which said signal producing means comprises a resolver having a rotor winding and a cosine stator winding, means for producing a signal proportional to the product of the mass of a round

fired by said gun and the rate of fire of said gun and the distance of the gun mount from the center of gravity of said platform, means for applying said product signal to said rotor winding, means responsive to movement of said line of fire for moving said rotor winding to cause said stator winding to provide said disturbing torque signal, and in which said compensating torque applying means is an electromagnetic reaction device comprising a pair of members relatively movable around said axis, means mounting one of said members on said platform for movement therewith, one of said members being energizable to generate a reaction torque between said members and a normally open switch actuatable concomitantly with the firing of the gun for applying said disturbing torque signal to said compensating torque applying means.

15. A system as in claim 1 in which said signal producing means comprises a resolver having a rotor winding and a cosine stator winding, means for producing a signal proportional to the product of the mass of a round fired by said gun and the rate of fire of said gun and the distance of the gun mount from the center of gravity of

said platform, means for applying said product signal to said rotor winding, means responsive to movement of said line of fire for moving said rotor winding to cause said stator winding to provide said disturbing torque signal, and in which said compensating torque applying means comprises a control surface adapted to be actuated to apply a torque to said platform, means including a servo loop for actuating said surface, a feel datum trim unit, means responsive to said feel datum trim unit for modifying said product signal to compensate for changes in the center of gravity of said platform and a normally open switch actuatable concomitantly with the firing of the gun for applying said disturbing torque signal to said compensating torque applying means.
